UNITED STATES PATENT OFFICE

96,162

DESIGN FOR A VENDING MACHINE

Edward E. Collison, Chicago, and Claude R. Kirk,
Oak Park, Ill., assignors to Standard Ticket
Games Corporation, Chicago, Ill., a corporation
of Illinois

Application April 25, 1935, Serial No. 56,561

Term of patent 14 years

To all whom it may concern:

Be it known that we, Edward E. Collison and Claude R. Kirk, citizens of the United States and residents of Chicago and Oak Park, respectively, in the county of Cook and State of Illinois, have invented a new, original, and ornamental Design for a Vending Machine, of which the following is a specification, reference being had to the accompanying drawing, forming a part thereof, and in which:

Fig. 1 is a perspective view of a vending machine showing our new design; and

Fig. 2 is a top plan view of the same, partly in section, on line 2—2 in Fig. 1;

We claim:

The ornamental design for a vending machine as shown.

EDWARD E. COLLISON.
CLAUDE R. KIRK.
